APPARATUS FOR INSERTING ELONGATED TAILED OBJECTS INTO OPEN-TOPPED RECEPACLES

Fred C. Gleason, Cannondale, Conn., assignor to American Home Products Corporation, New York, N.Y., a corporation of Delaware

Filed Oct. 16, 1962, Ser. No. 230,963

14 Claims. (Cl. 29—208)

This invention relates generally to apparatus for inserting objects of substantially similar configuration into receptacles therefor. More particularly, the invention relates to apparatus for automatically inserting one each of a series of elongated objects each consisting essentially of a structural enlargement at one end and a tail portion extending from said enlargement, into a respective one of a series of open-topped receptacles.

Although not restricted thereto, the invention is particularly useful for inserting one each of a series of valves, each comprising a cap or cup containing the valve mechanism and a dip tube dependent from said cup, into a respective one of a series of aerosol cans or containers conveyed on a feed line, preparatory to sealing of the aerosol valves to the containers and the filling of the latter with the dispensable fluid product and propellant. With the ever-widening acceptance of the packaging of fluid products in aerosol containers, it has become an increasingly greater problem to provide dependable, rapidly operating, substantially fully automatic means for such preparatory insertion of large quantities of aerosol valves into containers, to replace conventional laborious, time-consuming and costly manual operations. Moreover, increasing proportions of aerosol valves that are entirely of non-ferrous material are supplanting the formerly conventional aerosol valves comprising a cap of ferrous material and a non-ferrous dip tube. Hence, the use of the action of a magnetic field on the ferrous material cap during the inserting process, as has been taken advantage of in certain prior object-inserting machinery generally, is not now always feasible. Other elongated tailed objects of, for example, plastic materials, such as integral dauber and stopper assemblies, dropper-cap units, and the like, present similar problems with respect to insertion thereof, by appropriate machinery, into the containers the tailed objects are destined for.

With the foregoing in view, it is a primary object of the present invention to provide a comparatively simple, highly efficient and economic apparatus for automatically and continuously inserting one each of a plurality of elongated tailed objects into a respective one of a plurality of open-topped receptacles.

It is another object of the invention to provide such apparatus which performs the desired inserting operation regardless of the nature of the materials from which the objects being inserted are made.

It is another object to provide apparatus of the character referred to above wherein the objects to be inserted are fed to the inserting mechanism thereof automatically and in oriented condition.

It is another object of the invention to provide such apparatus which positively assures the feeding of one of the oriented objects to said inserting mechanism thereof only when an open-topped receptacle is present for the insertion action.

Another object is to provide such inserting apparatus wherein the receptacles into which the objects are being inserted are automatically fed singly into the device.

2

Yet another object of the invention is to provide an object-inserting apparatus capable of inserting previously oriented elongated tailed objects into open-topped receptacles at a rate upwards of 150 objects per minute.

5 It is another object of the invention to provide apparatus of the character referred to above and which is of particular utility for inserting aerosol valves in aerosol containers preparatory to the sealing of such valves to said containers and the filling of the latter with the fluid to be dispensed and the propellant therefor.

Other objects and advantages of the invention will become apparent as a result of a better understanding thereof upon reference to the following description.

Generally, the invention resides in apparatus comprising a plurality of inclined chutes each adapted to receive an elongate tailed object and to conduct it downwardly tail first, means for moving said chutes laterally through a predetermined path, a first feeding means in said path for supplying an upright, open-topped container beneath the lower end of a respective one of said chutes while in said path, means for maintaining each of said containers beneath a respective one of said chutes for a predetermined portion of said path, and second feeding means in said path for supplying an elongate tailed object tail down to a respective one of said chutes as the latter is in said portion of said path.

Preferably, the inclined chutes are mounted radially of a vertically disposed axially rotatable mounting stanchion or on an endless belt movable about vertically disposed axes for the purpose of moving the chutes laterally through said predetermined path. The inclined chutes are preferably open at their upper sides to facilitate introduction of the elongate tailed objects thereto by said second feeding means. For the purpose of keeping the open-topped containers, that have been supplied upright to the bottom end of a respective one of said inclined chutes, in continuous alignment with the lower end of a respective chute moving through said predetermined portion of said path; it is preferred to have separate container abutting and retaining means mounted for movement with a respective chute. To assure proper entry of the elongate objects received in the chute and moving downwardly tail first, into the open-top of the container positioned therewith, there is preferably provided in at least a section 40 of said predetermined portion of said path, a laterally elongate guide surface which cooperates with the lower end of the chutes moving therewith to form therewith respective open-bottom funnels. The open-bottomed funnels function to permit the tails of the elongate objects to extend therethrough but retain the larger upper ends of said objects within the formed funnel until the end of the guide surface is reached by the laterally moving chute. Desirably, automatic means are also provided for causing 45 positive feeding of an elongate tailed object from said second feed means in response to proper alignment of an inclined chute therewith. Preferably, in connection with said positive feeding means there are provided feed blocking means which render said positive feeding means inoperative if a chute moves therewith without an open-topped container aligned therewith.

Container take-off means are advantageously provided to positively remove containers from the path of the chutes after the elongated tailed objects are properly positioned within the open tops of said containers. Means 50 may be provided for positively causing the first feeding means to be rendered operative for supplying an open-topped container beneath each of said chutes in synchrony with the movement of the chutes.

Container take-off means are advantageously provided to positively remove containers from the path of the chutes after the elongated tailed objects are properly positioned within the open tops of said containers. Means 55 may be provided for positively causing the first feeding means to be rendered operative for supplying an open-topped container beneath each of said chutes in synchrony with the movement of the chutes.

nization with the positioning of the chute at a predetermined container loading station.

Several preferred embodiments of our invention are disclosed in the following description and drawings. It will be understood that the description and drawings are intended to be illustrative only and not to limit the invention, the scope of which is defined in the appended claims. Referring now to the drawings;

FIG. 1 is a vertical cross-sectional view of an aerosol valve-inserting apparatus in accordance with one embodiment of the invention, the section being taken along lines 1—1 of FIG. 2;

FIG. 2 is a plan view of the entire apparatus of which a part is seen in the vertical cross-sectional view of FIG. 1;

FIG. 3 is an enlarged fragmentary view of the feed chute and the upper region of one of the gravity filling chutes of the apparatus shown in FIGS. 1 and 2, the gravity feed chute being shown in the same operative relationship with said feed chute as shown in said figures;

FIG. 4 is a cross-sectional view of the feed chute and gravity filling chute shown in FIG. 3 and taken along section line 4—4 of the latter, but with the relationship of parts as the gravity filling chute approaches the feed chute being shown in full line, and the relationship of the pick-off lever mounted on the gravity chute with the cup of an aerosol valve assembly supported in the feed chute, under normal operative conditions when an aerosol can is available for filling, being shown in broken lines;

FIG. 5 is a cross-sectional view of the same parts shown in FIG. 4 but under circumstances where no aerosol can be available for filling and the pick-off lever is deflected from engagement with the aerosol valve cup in the feed chute, by the extension member of the solenoid core;

FIG. 6 is an enlarged fragmentary plan view of the device shown in FIGS. 1—5 but with one gravity filling chute moving clockwise beyond the feed chute as the next gravity filling chute approaches said feed chute, to illustrate more clearly the structural arrangement and operation of various parts;

FIG. 7 is a vertical cross-sectional view of an aerosol valve-inserting apparatus in accordance with another embodiment of the invention, the section being taken along lines 7—7 of FIG. 8;

FIG. 8 is a plan view of the entire apparatus seen in part in the vertical cross-sectional view of FIG. 7; and

FIG. 9 is a perspective view of an aerosol valve assembly illustrative of the type of elongated tailed objects that may be inserted into open-topped receptacles by apparatus in accordance with the present invention.

Referring to FIGS. 1 and 2, this embodiment of the invention comprises a main support shaft 2 on which is rotatably mounted a mounting sleeve or stanchion 3, by bearing means not visible. Affixed to mounting sleeve 3 for rotation therewith is a pulley in the sheave of which is mounted an endless driving belt 5 connected to driving means (not shown) for rotating the sleeve 3 in a clockwise direction as viewed in FIG. 2. Also affixed to mounting sleeve 3 for rotation therewith is a circular container support 6. Above circular container support 6 and similarly mounted on sleeve 3 for rotation therewith is a star wheel 7. Each of the arms of star wheel 7 is contoured to permit rolling of a container c along the outer surface 9 thereof until the container is received within the contoured cut-out 10 and retained therein by the inner surface 11 of arm 8 as star wheel 7 rotates with sleeve 3. Affixed to the top of mounting sleeve 3 also for rotation therewith is a mounting block 12 of generally hexagonal shape in plan (FIG. 2) but with sloping sides 13 (FIG. 1) for a purpose now to be described.

To each of sloping sides 13 of mounting block 12, there is respectively attached an inclined chute 14, by

means of its respective bottom edge 15. As seen in FIG. 1, due to the slope of sides 13 of hexagonal mounting block 12, chutes 14 mounted thereon are also sloped downwardly and outwardly. Each of inclined chutes 14 comprises a pair of substantially flat walls 16 inclined downwardly and inwardly toward each other and having the lower adjacent edges thereof comprising in conjunction the common bottom edge 15 to form a substantially V-shaped open-ended and open-topped inclined trough 17. Each pair of walls 16, of a respective chute 14 which they form, are disposed at an angle of inclination toward each other that is substantially equal to the angle of inclination of said chute, and the respective lower ends of said pairs of walls 16 terminate in straight edges 18 each disposed at an angle of inclination substantially equal to said angle of inclination of said walls 16 and said chute 14 for a purpose that will appear hereinafter. For this same purpose later to be described, the lowermost edge of each chute is horizontally truncated at 19.

Main stationary support shaft 2 has stationarily affixed to the top thereof, a mounting sleeve 20. Mounting sleeve 20 carries an upper bracket 21 having two arms 22 and 23 that respectively have horizontal portions 24 and 25 which diverge outwardly from each other, and vertical portions 26 and 27 that extend downwardly in substantially parallel relationship to each other. Carried by the lower ends of the vertically disposed bracket arm portions 26 and 27 is a funnel-completing plate 28 which is generally of an arcuate shape about shaft 2 as axis, and is disposed circumferentially of a portion of the circular and inclined imaginary surface described by the lower inclined edges 18 of chutes 14 as they rotate about shaft 2. Funnel-completing plate 28 has an angle of inclination substantially equal to that of said lower edges 18 of chutes 14 and is positioned by bracket 21 adjacent said edges 18 of chutes 14, whereby the latter may sweep by the inner surface 29 of plate 28 almost in contact therewith and with the bottom edge 30 of plate 28 substantially horizontally aligned with truncated edge 19. With this arrangement, three-sided funnels 31 are formed with bottom openings 32 during the period that chutes 14 sweep by plate 28.

Mounted on the lower portion of mounting sleeve 45 20 is a second bracket 33 which has the arms 34 and 35 thereof extending outwardly (FIGS. 1 and 2) and downwardly (FIG. 1). Bracket arms 34 and 35 are connected at the respective lower ends thereof to the lower end 36 of an inclined aerosol valve and dip tube 50 assembly feed chute 37 for supporting the same. The upper end of feed chute 37 is connected to and supported by means not shown.

As best seen in FIGS. 3—6, feed chute 37 comprises a lower pair of spaced parallel strips 38 and 39 forming 55 a lower slot 40 therebetween and an upper pair of spaced parallel strips 43 and 44 defining an upper slot 46 therebetween. Upper strips 43 and 44 are respectively aligned with and spaced above lower strips 38 and 39 whereby slots 40 and 46 are in alignment and a channel 47 is 60 defined between said upper and lower strips. The exterior sides of strips 38, 39, 43 and 44 are attached as by welding to the interior surfaces of each of a plurality of generally rectangular brackets 48, whereby said four aligned strips are maintained in the stated relationships. 65 Each bracket 48 has a discontinuity or slot 49 at its bottom in general alignment with slot 40 and a lower vertically disposed cut-out section 49a in its top reach in general alignment with slot 46, and a pair of horizontally disposed cut-out portions 49b in its inner side reaches in general alignment with channel 47. Thus, chute 37 is adapted to permit aerosol valve and dip tube assemblies 70 42 to slide down therein under the influence of gravity with the valve housings or cups 45 of said assemblies riding over the upper surfaces of said strips 38 and 39 in guided manner with the dip tubes 41 of said assemblies.

protruding downwardly through lower slot 40 (and slots 49 as the dip tubes 41 move therewith), and the valve stems 41a protruding upwardly through upper slot 46.

Upper strips 43 and 44 are additionally connected as at their lower ends by an integral cross strip 50a (FIG. 6) which has depending therefrom a flange 50 (FIG. 3). Depending flange 50 in turn has at its lower end an inward flange 51 directed towards but short of the truncated ends 52 of lower strips 38 and 39 and hence in effect functions as a continuation therefor with respect to support of the cups 45 of aerosol valves 42 which reach the lowermost end of chute 37. The ends 52 of lower strips 38 and 39 and inturned flange 51 are spaced from each other to define therebetween a lower slot 53 disposed transversely of lower slot 40. Upper strip 44 is provided with a bridge 54 therein having the higher reach 55 thereof extending beyond and hence clearing the top extremity of the valve actuator piece 41a of an aerosol valve assembly 42 which may become positioned in the lower end of chute 37 with the cup 45 of the assembly abutting flange 50.

Affixed to the bottom surface of lower strip 38 is a generally rectangular bracket plate 56 having a contoured end 57 on the upper surface of which is fixedly mounted a solenoid 58. Solenoid 58 has the usual core piece (not visible) which in this case has at one end thereof an extension 59 protruding therefrom and provided with a spring-retaining flange 60. The other end of the core piece has mounted thereon an abutment piece 62 comprising a downwardly extending arm 63. An expansion spring 61 encircles extension 59 and is maintained under compression between retaining flange 60 and the proximal end of solenoid 58 to urge the core to the left as viewed in FIGS. 3 and 6, and with it the described structures mounted thereon, to the full line position shown in FIGS. 3 and 6. Upon energization of solenoid 58, the core thereof is centered and hence moved to the right (FIGS. 3 and 6) against the action of spring 61, whereupon abutment piece 62 carrying downwardly extending arm 63 assumes the broken line position *b* shown in FIG. 6.

Energization of solenoid 58 is controlled by a conventional toggle switch 64 mounted on strip 43 of chute 37 and connected in lead lines 65 from a source of electricity indicated schematically. Switch 64 has the toggle 66 thereof normally biased by the usual spring means (not visible) to the "off" position shown in full lines in FIG. 6. Toggle 66 is movable against the action of said interior spring means to the "on" position shown in broken lines in FIG. 6. The means for moving toggle 66 to said "on" position are now described below.

A container-sensing arm 70 is pivotally mounted at one of its ends by means of a spindle 70a and has affixed thereto, and spaced from said end, a short shaft 70b. Arm 70 has attached to the free feeler end thereof a spring 71 which biases said arm 70 to the broken line position shown in FIG. 6 when the absence of a container *c* beneath a respective chute 14 allows this to occur. A containersensing linkage arm 67 is pivotally mounted intermediate its ends by means of a spindle 68 affixed to a bracket 69 mounted adjacent container support 6. Linkage arm 67 has a slot 67a extending longitudinally in one end thereof and in which short shaft 70b of arm 70 rides. Arm 67 is provided at the other end thereof with a toggle-operating portion 73, which, when pivoted to the broken line position shown in FIG. 6, functions to push toggle 66 of switch 64 to the broken line position also shown in FIG. 6. As will also appear from FIG. 6, when spring 71 biases sensing arm 70 to said broken line position, linkage arm 67 is caused by shaft 70b riding in slot 67a to pivot to said broken line position thereof. In such position, the toggle-operating end 73 of arm 67 pushes toggle 66 to said "on" position whereupon solenoid 58 is energized.

In the presence of a container *c* within a contoured cutout 10 of star wheel 7 in the region adjacent chute 37, feeler end 70 is pushed by the side surface of the container to the full line position. Toggle switch operator end 73 is thus pivoted away from abutment with toggle 66 to the position shown in full lines in FIG. 6. The toggle then assumes the full-line "off" position to which it is normally biased, and causes de-energization of solenoid 58.

Each chute 14 has affixed thereto, at the upper edge of the wall 16 thereof that trails during the clockwise rotation (FIG. 2) of all the chutes 14 with hub 12, a hinge bracket 74 (FIG. 3). On the hinge pin 75 of bracket 74 there is pivotally mounted a generally L-shaped ejector finger 76, as by the lower end 77 of the latter. A spring 78 is mounted on the lower surface of each of said trailing walls 16 of chutes 14 by means of a shallow U-shaped bracket 79 (FIGS. 3 and 6). The lower end 80 of each spring 78 bears against said lower surface of wall member 16 and the upper end 81 of spring 78 bears against the lower reach of L-shaped ejector finger 76 to urge the latter towards its normal upright position best seen in FIGS. 3 and 4. Spring 78 is chosen to be of sufficient strength to maintain ejector finger 76 in said normal upright position against, say, the free weight of an aerosol valve assembly 42, but to yield easily upon contact of finger 76 with an abutment, for reasons that will appear hereinafter. A stop lug 82 (FIGS. 4-6) is mounted on the interior or upper surface of the respective trailing wall 16 and limits the pivotal movement of ejector finger 76 to its normal upright position as appears in FIG. 4. Ejector finger 76 is generally located on wall 16 whereby the upper reach 83 of finger 76 is so positioned with respect to channel 53 (through lower strips 38 and 39 of said chute 37) and channel 47 (between upper strips 43 and 44 and lower strips 38 and 39) so that said reach 83 may ride laterally through said channels 53 and 47 as the chutes 14 revolve in said clockwise direction.

An endless feed belt 84 of substantially the width of the containers *c* to be delivered to the inserter mechanism, and provided with guide rails 85, approaches adjacent the periphery of container support 6 in a direction substantially radially thereof and at the same level thereof. A second endless belt 86 is provided adjacent the periphery of container support 6 and is similarly provided with guide rails 87. However, in this case, endless belt 86 has the flexible web thereof starting with its end 88 beneath container support 6 and generally tangentially thereof and extending in relation to the latter to pick up containers moving off container support 6 and to convey them to another location (not shown) where other operations may be performed. Endless belts 84 and 86 are provided with suitable driving means (not shown) for moving said belts in the direction of the respective arrows. To aid in the removal and guidance of containers *c* from the contoured cut-outs 10 of star wheel 7, there is provided an endless guide belt 88 mounted on pulleys 89 and 90 which are respectively affixed to shafts 91 and 92 for rotation therewith. Shaft 92 is provided with a second pulley 93 affixed thereto on which is mounted an endless driving belt 94 connected to conventional driving means not shown.

In the operation of the device described above, chute 37 is loaded with a plurality of properly oriented aerosol valve assemblies 42 (FIG. 1) by any suitable means manually or automatically. A particularly useful automatically operating device for providing the aerosol valve assemblies 42 to chute 37 in the properly oriented relationship shown, is disclosed and claimed in my co-pending application Ser. No. 178,996 filed March 12, 1962. Thereafter, the driving means for endless belts 84 and 85, guiding and take-off endless belt 88, and mounting sleeve 3, are rendered operative. Containers *c* are fed (manually or automatically by means not shown) to end-

less belt 84 which conveys said containers toward star wheel 7 and container support 6. As star wheel 7 rotates clockwise and presents a contoured surface 9 leading to a contoured cut-out portion 10 to the discharge end of belt 84, the lead container c thereon is caused to roll along surface 9 until it is seated within the respective cut-out portion 10 defined by finger 8. Thus, a container c is positioned with its open top immediately beneath the lowermost open extremity 19 of the chute 14 above said cut-out 10. As each chute 14, with a container c positioned therebelow approaches chute 37, the outwardly facing periphery of said container c abuts feeler end 70 of sensing arm 67. Arm 67 is thus pivoted outwardly on spindle 68 against the biasing action of spring 71 whereby the toggle operator end 72 of said arm 67 is pivoted out of contact with toggle 66 to permit it to assume its normal "off" position shown in full lines in FIGS. 3-6. Solenoid 58 is accordingly de-energized whereupon compression spring 61 urges extension 59 and with it abutment piece 62 to the full line position shown in FIG. 6. With abutment piece 62 and arm 63 thereon withdrawn, ejector finger 76 mounted on wall 16 of chute 14 is not deflected from its upright position shown in full lines in FIG. 4 and maintains such position as reach 83 of ejector finger 76 moves into abutment with the valve portion 45 of the aerosol valve assembly 42 positioned in the lowermost region of chute 37 (as indicated in broken lines in FIG. 4). Reach 83 of ejector finger 76 then continues to bear on valve portion 45 of the assembly 42 and pushes the latter laterally to the right as viewed in FIG. 4, through channel 47, as finger 76 is maintained in upright position by spring 78. As aerosol valve assembly 42 is continued to be urged by upright finger 76 to the right as viewed in FIG. 4, the valve finger piece 41a of assembly 42 thereof passes beneath bridge 55 and the dip tube 41 thereof passes through channel 53 as does ejector finger 76. The aerosol valve assembly 42 then drops off said feed 37 and into chute 14 with dip tube 41 lowermost. Assembly 42 then slides downwardly in the chute 14 under the influence of gravity and because of the inwardly inclined walls 16 ultimately settles with the valve portion 45 riding in the lowermost part of the V of chute 14 that will accommodate the diameter of said valve portion 45.

At about the same time that a chute 14 is approaching the region of chute 37, the inclined end 18 of said chute 14 wipes by funnel-completing plate 28. During the time that said chute continues its lateral movement adjacent said plate 28, the valve assembly 42, dropped into the chute, moves downwardly therein. The three-sided funnel formed by walls 16 of chute 14 and plate 28 directs the dip tube 41 of assembly 42 until dip tube 41 enters and then drops through opening 32 provided in the bottom of the funnel by truncated edge 19, and continues downwardly into the open upper end of the container c therebelow. Valve assembly 42 continues its descent until it is stopped from further entry into the container c by the narrowing funnel surfaces presented by said walls 16 and plate 28 to the lower periphery of valve cap 45 of said assembly 42.

As the aforesaid container c continues to be moved by star wheel 7 and container support 6 toward the beginning of endless belt 86, said container abuts said guide belt 88. Belt 88, being athwart the circular path of the container and moving in the direction of the arrows, causes ultimate removal of the container from the contoured cut-out in star wheel 7 and off support 6, and finally, deposit of said container on the upper surface of endless belt 86. During this same time, as chute 14 clears plate 28, the aerosol valve assembly 42 therein is free to drop substantially completely into the open upper end of the container therebelow. Endless belt 86 then conveys the container c with the aerosol valve assembly fully positioned therein to a crimping station (not shown) at which the inserted valve assembly 42 may be perma-

nently affixed to said container prior to conventional filling thereof.

In the event that a contoured cut-out 10, for any reason at all, does not have a container c positioned therein below the associated chute 14, as said chute approaches the region of said feed chute 37, sensing arm 67, in such case, will not be pivoted against the biasing action of spring 71 to the full line position shown in FIG. 6. Instead, sensing arm 67 will assume the broken line position shown which causes the toggle operating end 73 thereof to position toggle 66 to the "on" position shown in broken lines. The closing of switch 64 energizes solenoid 58 whereupon the core thereof (not visible) is centered against the biasing action of spring 61 and causes arm 62 to extend to the broken line position. In such positioning of the parts, downward extension 63 on arm 62 is located in the path of the next on-coming ejector finger 76. Extension 63 then functions to deflect ejector finger 76 backwardly against the biasing action of spring 78, as illustrated in FIG. 5. As the chute 14 continues its movement in the direction of the arrow, ejector finger 76 is released and is moved towards its upright position by spring 78. Since said chute 14 is moving laterally at the same time, ejector finger 76 does not assume its upright pick-off position (FIG. 4) until chute 14 has sufficiently cleared feed chute 37, to render finger 76 inoperative for its valve assembly pick-off function. Thus, it is assured that no aerosol valve assembly 42 is picked-off feed chute 37 and dropped into a chute 14 which does not have a container c therebelow ready to receive a valve assembly.

Reference is now made to the preferred embodiment of the invention disclosed in FIGS. 7 and 8. In this embodiment, a rotatable shaft 102 mounted in an upper bearing 35 and bracket support member 120 and a lower bearing member (not shown), has affixed thereto for rotation therewith a stanchion 103 of hexagonal cross-section, each face of which has mounted substantially centrally thereof a gear tooth 106. An endless belt 112, comprising separate plate sections 113 connected at their vertical edges by pivotal hinge connectors 113a, is mounted on said hexagonal stanchion 103. The plates 113 are each provided with an aperture 115 with which gear teeth 106 are in alignment. Affixed on said shaft 102 below stanchion 103 is a gear 104 on which is mounted driving chain 105 connected to driving means (not shown). A second stanchion shaft and bracket support assembly (not shown) similar to the assembly described above, is mounted at the other end of the device and supports the other end of endless belt 112 to permit driving of the endless belt on said stanchions in the direction of the arrows by said gear 104 and driving chain 105.

Each of plates 113 has affixed thereto a chute 114 of substantially similar construction to chutes 14 of the embodiment of the invention disclosed in FIGS. 1-6. Thus, each chute 114 comprises a pair of inclined walls 116 each having the lower edge thereof terminating in a sloping extremity 118 and being truncated at the lowermost end 119 to provide an aperture 132. Each chute 114 is maintained at a predetermined slope with respect to the substantially vertically disposed plates 113 by mounting means 113b. Also mounted on each plate 113 but at the lower trailing edge thereof is an elongate arm 108 which functions to engage and move containers c therewith as described in greater detail hereinafter.

An inclined feed chute 137 is positioned so that its discharge end is immediately above the path of chutes 114 as they pass a straight segment of said path. Feed chute 137 is of generally similar construction to feed chute 37. Said feed chute 137 comprises lower strips 138 and 139 and upper strips 143 and 144 which are held in proper relationship by a plurality of generally rectangularly-shaped brackets 148 provided with similar vertical and horizontal cut-out portions 149, 149a and 149b as in brackets 48 to permit clearance of the dip tubes 41, valve

finger pieces 41a and cups 45 of the aerosol valve assemblies 42 sliding down therein. The lower end of said chute 137 is supported by a bracket 121 mounted on the mounting sleeve 120 in which shaft 102 rotates. Also supported by bracket 121 are a solenoid 158 and an escapement supporting bracket 167 of substantially L-shape. Pivotaly mounted at the free extremity of L-shaped bracket 167 by means of a pivot pin 168, is a generally shallow U-shaped escapement lever 176 having the downwardly extending ends 170 and 173 spaced apart a slightly greater distance than the diameter of the valve cups 45 of the assemblies 42 sliding in chute 137. The core piece (not visible) of solenoid 158 has connected thereto extension arm 162, the lower end of which is pivotally connected at 163 to escapement lever 176 adjacent end 173 thereof. Also supported by bracket 121 is a funnel-completing plate 128, which in this case is of generally flat rectangular configuration. As in the previous embodiment, plate 128 is positioned and maintained closely adjacent the path of the sloping edges 118 of chutes 114.

An endless belt 184 is positioned with an edge thereof adjacent the line of travel of plates 112 as the latter move through one portion of their straight path. Endless belt 184 is mounted on a pair of rollers, one of which is shown in FIG. 7 at 188. Roller 188 is affixed to a shaft 189 mounted for rotation in bearings 190 provided in a pair of stanchions 191. Affixed to one end of shaft 189 is a pulley 192 on which is mounted a driving belt 193 connected to driving means not shown. Endless belt 184 has a width substantially greater than twice that of the containers c that are conveyed thereby for the purposes that will now appear.

Over the upper surface portion of said endless belt 184 there are maintained in parallel relationship, a pair of guide rails 185 for directing containers c along the surface of the half of the width of endless belt that is remote from the path of plates 113 bearing chutes 114. Guide rails 185 terminate at 186 in the region where chutes 114 move from their generally arcuate path about stanchion 103 and into the straight portion of their path on their way to the second stanchion (not shown). A second solenoid 195 is provided which has attached to the core (not visible) an extension 159 with an end flange 160 retaining on extension 159 a spring 161. At the other end of the core of solenoid 195 there is affixed a flat surfaced pusher member 185a, the vertical surface thereof functions as an extension of the guide rail 185 located adjacent the extreme left edge of belt 184 as viewed in said FIGS. 7 and 8.

A combined stop and pressure switch member 196 is positioned directly in the path of containers c moving on endless belt 184 between guide rails 185. Pressure switch member 196 is urged by a light spring 197 away from a pair of contacts 198 located in conductor wire 165 which is connected into solenoid 195 and thence to one terminal of a source of electric power indicated schematically. The circuit is completed by a second conductor wire 165a which is connected through a toggle switch 199 to one of the contacts 198. Toggle switch 199 is of a conventional design wherein an interior spring (not visible) urges the toggle 200 to the full line "off" position shown in FIG. 8. As will be apparent from inspection of said figure, toggle 199 is positioned in the path of the distal ends of arms 108 whereby as each of said arms 108 sweeps by toggle 200, the latter is momentarily positioned to the "on" position indicated in broken lines. A guide rail 187 is positioned along endless belt 184 to maintain containers c (being carried by arms 108) against plates 113. Protruding through an aperture in said guide rail 187 is a push button 166 of a switch 164 connected by electric conductor leads 165b into leads 165 and 165a. Button 166 of switch 164 is urged outwardly to its normal "off" position by spring means (not shown) and controls energization of solenoid 158 via leads 165c.

In the operation of the embodiment of the invention described immediately above, as in the previous embodiment, the feed chute 137 is loaded with properly oriented aerosol valve assemblies 42. Since solenoid 158 is de-energized, core piece extension 162 is fully extended downwardly under the influence of gravity to hold the lower end 173 of escapement lever 176 in the path of the valve cup 45 of the lowermost assembly 42 to retain all assemblies 42 in chute 137. Similarly, containers c are supplied (by means not shown) to endless belt 184 between guide rails 185, as indicated in FIG. 8. Thereafter, the driving means (not shown) connected to driving belt 193 are rendered operative. As a result, endless belt 112, bearing chute assemblies 114, is caused to move continuously in the direction of arrow a, and endless belt 184 is caused to move in the direction of arrows b. Containers c advance between guide rails 185 until the lead container abuts pressure switch 196, to press it ultimately to switch-closing relationship with contacts 198 in the circuit to solenoid 195. As the next approaching arm 108 on a respective plate 113 bearing a chute 114 sweeps by toggle 200 of switch 199, said arm 108 pushes toggle 200 to the "on" position indicated in broken lines (FIG. 8) and, after clearing toggle 200, permits it to snap back to the normal "off" position shown in full lines. Thus, cyclically, as a space 110 between adjacent arms 108 is presented opposite pusher surface 185a, the circuit from the electric power source via leads 165 and 165a to solenoid 195 is fully completed momentarily. Solenoid core extension 159 is immediately urged towards the right as viewed in FIG. 8, against the biasing action of compression spring 161, and by means of pusher surface 185a ejects the container c abutting said surface 185a (and the now-closed pressure switch 196) towards plate 113 and into the space 10 between the arm 108 on the preceding plate 113 and the arm 108 which has just urged toggle 200 to the "on" position. Due to the fact that the speed of endless belt 184 is slightly slower than the lateral speed of endless belt 112, the ejected container c comes to rest in the space 110 against the leading edge of the arm 108. Said container c, upon abutment with guide rail 187, is urged against plate 113 and is thereby properly aligned beneath the respective chute 114, as is illustrated in FIG. 8.

Upon ultimate abutment of the outer peripheral surface of container c with push button 166 of switch 164, the electric circuit is momentarily completed to solenoid 158 via leads 165a and 165b. Thereupon, the core extension piece 162 thereof is pulled upwardly and with it the lower end 173 of escapement 176 to cause counter-clockwise pivoting of the latter on pivot 168. Thus, the lowermost valve assembly 42 is released to slide off the lower open end of feed chute 137 and drop into a chute 114 then aligned therewith. The valve assembly 42 that was immediately behind the one just released is, at this time, prevented from descending any further than the upper end 170 of escapement 176 which abuts the valve actuator piece 41a of said valve assembly.

As soon as said container c clears push button 166, the latter is spring-biased to protruding "off" position, whereby solenoid 158 is de-energized. The core and its extension 162 drops under the influence of gravity and the escapement lever 176 again assumes the position shown in FIG. 7. With end 170 of escapement lever 176 lifted and end 173 thereof lowered, assemblies 42 slide downwardly in chute 137 under gravity until the leading assembly 42 is stopped upon abutment with lowered end 173. Feed chute 137 and the associated release mechanism is thus set for the next succeeding feeding cycle upon momentary closure of switch 164 by the next advancing container c. Obviously, if for some reason a container c is not located beneath the chute 114 aligned with feed chute 137, push button 166 of switch 164 is merely not actuated and no valve assembly 42 released.

Prior to abutment of a container *c* with push button 166, the chute 114 associated with the arm 108 mounted on the same plate 112 passes in sweeping alignment with funnel-completing plate 128 to form a three-sided funnel having a lower opening 132 in the bottom thereof. The valve assemblies 42 descend in the respective chutes 114 and into the bottom of the formed funnels in the same manner as in the previous embodiment. However, in this case funnel-completing plate 128 may be extended to the length considered necessary to permit complete settling of the aerosol valve assembly 42 in the lower portion in the formed funnel, even though the funnels (and of course endless belts 184) are moving at a continuous and comparatively rapid rate.

While several preferred embodiments of the invention have been described in detail above, as will readily appear to those skilled in the art, various modifications thereof are possible without departing from the spirit of the invention defined in the appended claims. Merely by way of example of the variations possible, chain or other drives may be substituted for belt drives, and vice versa; the slopes of the various chutes may be varied from those shown, other container-feeding, guiding and take-off means may be substituted for those illustrated; similarly, the assembly feeding device may be modified in certain instances. Also, the loading chutes may be caused to travel in an endless path not necessarily horizontally disposed, but may be at an angle thereto. Hence, it will be understood that the term "laterally," as used herein and in the appended claims, is intended to encompass directions varying from the horizontal to the extent where the intended operations and functions of the device in accordance with the invention may still be performed.

I claim:

1. Apparatus for inserting elongate tailed objects into open-topped containers, said apparatus comprising a plurality of inclined chutes each adapted to receive an elongate tailed object and to conduct it downwardly tail first, means on which said chutes are mounted in laterally adjacent relationship, means for moving said mounting means with said chutes thereon laterally through a predetermined path, a first feeding means, means mounting said first feeding means for discharge in said path for supplying substantially upright open-topped containers beneath the lower discharge end of a respective one of said chutes while in said path, means mounted adjacent said path for maintaining each of the containers beneath a respective one of said chutes for a predetermined portion of said path, second feeding means, and means mounting said second feeding means for discharge in said path for supplying an elongate tailed object tail down to a respective one of said chutes as the latter is in said portion of said path.

2. Apparatus for inserting elongate tailed objects into open-topped containers, said apparatus comprising a plurality of inclined chutes each adapted to receive an elongate tailed object and to conduct it downwardly tail first, means on which said chutes are mounted in laterally adjacent relationship, means for moving said mounting means with said chutes thereon laterally through an endless predetermined path, a first feeding means, means mounting said first feeding means for discharge in said path for supplying a substantially upright open-topped container beneath the lower discharge end of a respective one of said chutes while in said path, means mounted adjacent said path for maintaining each of the containers beneath a respective one of said chutes for a predetermined portion of said path, laterally elongate guide surface means, means mounting said guide surface means for extending in said path adjacent the lower ends of said chutes to form therewith respective open-bottom funnels, second feeding means, and means mounting said second feeding means for discharge in said path for supplying an elongate tailed object tail down to a respective one of said chutes as the latter is in said portion of said path.

respective one of said chutes as the latter is in said portion of said path adjacent said guide surface means.

3. Apparatus for inserting elongate tailed objects into open-topped containers, said apparatus comprising a plurality of inclined chutes each adapted to receive an elongate tailed object and to conduct it downwardly tail first, means on which said chutes are mounted in laterally adjacent relationship, means for moving said mounting means with said chutes thereon laterally through an endless predetermined path, a first feeding means, means mounting said first feeding means for discharge in said path for supplying a substantially upright open-topped container beneath the lower discharge end of a respective one of said chutes while in said path, means mounted adjacent said path for maintaining each of the containers beneath a respective one of said chutes for a predetermined portion of said path, laterally elongate guide surface means, means mounting said guide surface means for extending in said path adjacent the lower ends of said chutes to form therewith respective open-bottom funnels, second feeding means, means mounting said second feeding means for discharge in said path for supplying an elongate tailed object tail down to a respective one of said chutes as the latter is in said portion of said path adjacent said guide surface means, and means responsive to positioning of each of said chutes in said path in object-receiving relationship with said second feeding means for rendering the latter operative.

4. Apparatus for inserting elongate tailed objects into open-topped containers, said apparatus comprising a plurality of inclined chutes each adapted to receive an elongate tailed object and to conduct it downwardly tail first, means on which said chutes are mounted in laterally adjacent relationship, means for moving said mounting means with said chutes thereon laterally through an endless predetermined path, a first feeding means, means mounting said first feeding means for discharge in said path for supplying a substantially upright open-topped container beneath the lower discharge end of a respective one of said chutes while in said path, laterally elongate guide surface means, means mounting said guide surface means for extending in said path adjacent the lower ends of said chutes to form therewith respective open-bottom funnels, means mounted adjacent said path for maintaining each of the containers beneath a respective one of said chutes for a predetermined portion of said path, second feeding means, means mounting said second feeding means for discharge in said path for supplying an elongate tailed object tail down to a respective one of said chutes as the latter is in said portion of said path adjacent said guide surface means, first sensing means responsive to positioning of each of said chutes in said path in object-receiving relationship with said second feeding means for rendering the latter operative, and second sensing means responsive upon lack of a container beneath each of said chutes as it is in object-receiving relationship with said second feeding means for preventing said first sensing means from rendering said second feeding means operative.

5. Apparatus for inserting elongate tailed objects into open-topped containers, said apparatus comprising a plurality of inclined chutes each adapted to receive an elongate tailed object and to conduct it downwardly tail first, means on which said chutes are mounted in laterally adjacent relationship, means for moving said mounting means with said chutes thereon laterally through an endless predetermined path, a first feeding means, means mounting said first feeding means for discharge in said path for supplying a substantially upright open-topped container beneath the lower discharge end of a respective one of said chutes while in said path, laterally elongate guide surface means, means mounting said guide surface means for extending in said path adjacent the lower ends of said chutes to form therewith respective open-bottom funnels, means mounted adjacent said path for maintaining

each of the containers beneath a respective one of said chutes for a predetermined portion of said path, second feeding means, means mounting said second feeding means in said path for supplying an elongate tailed object tail down to a respective one of said chutes as the latter is in said portion of said path adjacent said guide surface means, first abutment means mounted in said path and operative upon positioning of each of said chutes in said path in object-receiving relationship with said second feeding means for causing discharge of an object from said second feeding means, and second abutment means mounted in said path and responsive upon lack of a container beneath each of said chutes as it is in object-receiving relationship with said second feeding means for preventing said first abutment means from becoming inoperative.

6. Apparatus for inserting elongate tailed objects into open-topped containers as claimed in claim 5 wherein said second feeding means comprise an object guideway having a lateral channel therein and said first abutment means comprise a pick-off finger mounted on each of said chutes and positioned to pass through the lateral channel in said guideway as each of said chutes move therewith whereby an object is pushed off said second feeding means and dropped into each of said chutes.

7. Apparatus for inserting elongate tailed objects into open-topped containers, said apparatus comprising:

- (1) a vertically disposed shaft mounted for rotation;
- (2) a plurality of inclined chutes mounted on said shaft and disposed radially outwardly and downwardly thereof, said chutes being open at their upper sides and bottom edges and terminating in a lower sloping edge;
- (3) a circular container-supporting floor mounted on said shaft for rotation therewith a predetermined distance below said chutes whereby containers may be supported below said chutes;
- (4) container-abutting and retaining means also mounted on said rotatable shaft for rotation therewith, said abutting and retaining means being positioned between the lower ends of said chutes and above said floor, and said means having a plurality of arms each adapted to align and retain a container beneath a respective one of said chutes;
- (5) a substantially arcuate plate, means mounting substantially arcuate plate for extending horizontally in the path of the lower sloping edges of said chutes for a predetermined limited portion of said path, said plate being adjacent to and inclined along said sloping edges of said chutes and forming therewith separate funnels;
- (6) a feed chute for a plurality of elongate tailed objects, means mounting said feed chute for having the discharge end positioned above the path of said inclined chutes in the region of said open upper sides thereof;
- (7) means located on each of said inclined chutes for picking off a single object from said discharge end of said feed chute as each of said inclined chutes passes said feed chute;
- (8) means mounted adjacent said path for feeding containers to said container-supporting floor and said container-abutting and retaining means; and
- (9) means mounted adjacent said path for removing each container from said floor and said retaining means after the container has been filled with a respective object and has been carried clear of said arcuate plate.

8. Apparatus for inserting elongate tailed objects into open-topped containers as claimed in claim 7 wherein said container-abutting and retaining means (4) comprise a star-wheel having forwardly curved arms.

9. Apparatus for inserting elongate tailed objects into open-topped containers as claimed in claim 7 wherein said pick-off means (7) located on each of said inclined chutes comprise a pivoted arm resiliently biased to an extended

position in which said arm passes through said discharge end of said feed chute (6) when a respective one of said inclined chutes (2) moves therewith.

10. Apparatus for inserting elongate tailed objects into open-topped containers as claimed in claim 9 wherein an extendable abutment arm is located adjacent said discharge end of said feed chute and is positioned in the path of said pivoted arms when both said abutment arm and in approaching one of said pivoted arms are in extended positions; and means are provided for extending said extendable arm when one of said inclined chutes with said pivoted arm thereon approaches said discharge end of said feed chute without a container below said inclined chute and for maintaining said extendable arm in retracted position if a container is present below said inclined chute.

11. Apparatus for inserting elongate tailed objects into open-topped containers, said apparatus comprising:

- (1) a pair of spaced vertically disposed shafts mounted for rotation;
- (2) an endless vertically disposed belt comprising a plurality of hinged sections mounted on said shafts;
- (3) a plurality of inclined chutes each mounted on a separate one of said hinged sections and disposed outwardly and downwardly thereof, said chutes being open at their upper sides and bottom edges and terminating in a sloping edge;
- (4) a wide container-supporting movable floor mounted adjacent a straight region of said belt and positioned with a first portion of the width of said floor a predetermined distance below said chutes whereby containers may be supported below said chutes;
- (5) container-abutting and retaining means also on said hinged sections for movement therewith, said last named means being positioned between the lower ends of said chutes and above said first portion of said floor, said means comprising a plurality of arms each adapted to align and retain a container beneath a respective one of said chutes;
- (6) a substantially straight plate, means mounting said plate for extending horizontally in the path of the lower sloping edges of said chutes for a predetermined straight portion of said path defined by said floor, said plate being adjacent to and inclined along said sloping edges of said chutes and forming therewith with separate funnels;
- (7) a feed chute for a plurality of elongate tailed objects, means mounting said feed chute for having the discharge end positioned above said straight portion of said path of said inclined chutes in the region of said open upper sides thereof;
- (8) means operatively associated with said feed chute and responsive to the presence of a container beneath a respective one of said inclined chutes as said chute approaches said discharge end of said feed chute for dropping a single object from said discharge end of said feed chute;
- (9) means mounted adjacent said path for retaining containers on a portion of said container-supporting movable floor adjacent said first portion thereof and remote from said inclined chutes; and
- (10) means mounted adjacent said path for moving a single container at a time from said second portion of said floor to said first portion thereof and beneath a respective one of said chutes prior to approach of said chutes to said discharge end of said feed chute.

12. Apparatus for inserting elongate tailed objects into open-topped containers as claimed in claim 11 wherein said container-abutting and retaining means (5) mounted on said hinged sections has a part thereof which functions to actuate said means (10) for moving a single container at a time from said second portion of said floor to said first portion thereof.

13. Apparatus for inserting elongate tailed objects into open-topped containers as claimed in claim 11 wherein said floor (4) is an endless horizontally disposed belt mov-

15

able in the same direction as said endless vertically disposed belt (2) but at a slightly lesser speed.

14. Apparatus for inserting elongate tailed objects into open-topped containers as claimed in claim 12 wherein said means (10) for moving a single container at a time from said second portion of said floor to said first portion thereof is provided with sensing means for rendering said means (10) actuatable by said part of said container-abutting and retaining means only when a container is available to said means (10).
